ABRASIVE DRUM FOR LEATHER SURFACING
MACHINES AND THE LIKE

George Monroe Curtin, Gloversville, N. Y., assignor of one-half to Behr-Manning Corporation, Watervliet, N. Y., a corporation of Massachusetts, and one-half to Curtin and Hebert Company, Inc., Gloversville, N. Y., a corporation of New York

Application November 21, 1936, Serial No. 112,105

4 Claims. (Cl. 51—194)

The invention relates to abrasive drums.

One object of the invention is to provide an abrasive drum for holding sheet abrasive material for a leather surfacing machine which holds the sheet material very tightly. Another object of the invention is to provide a drum of the character indicated upon which may be mounted paper or other abrasive sheet material of parallelogram shape. Another object of the invention is to provide a drum which will hold the sheet material without wrinkles and which may be operated at high speed and under great pressure without tearing the abrasive sheet. Another object of the invention is to provide an abrasive drum of the character indicated which can be surfaced and resurfaced with abrasive paper or other abrasive sheet material very quickly and easily. Other objects will be in part obvious or in part pointed out hereinafter.

20 The invention accordingly consists in the features of construction, combinations of elements, and arrangements of parts, as will be exemplified in the structure to be hereinafter described, and the scope of the application of which will be indicated in the following claims.

25 In the accompanying drawings in which is illustrated one of many possible embodiments of the mechanical features of this invention,

Figure 1 is an axial sectional view of a drum constructed in accordance with the invention,

30 Figure 2 is a view, partly in end elevation and partly in cross section, of the drum,

Figure 3 is a longitudinal elevation of the drum.

35 Figure 4 is a plan view of the abrasive sheet material showing how it is cut,

Figure 5 is a transverse vertical sectional view of a leather surfacing machine incorporating the drum of the invention.

Referring first to Figure 1, I provide a horizontal shaft 10 constituting the axial shaft for the abrasive drum. I further provide a cylindrical drum 11 having an outer unbroken cylindrical surface, as indicated, made of cast iron or other suitable material and, if desired, made up in sections but joined by welding or the like to form a practically integral structure. The drum 11 has diametral web portions 12, 12 having hubs 13, 13 which are press fitted onto the shaft 10.

Pinned to the journal portions 13, 13 by means of pins 17 are a pair of holders 18, 18. In one end of the holders 18, 18 are journaled stud pinion gears 20 having grooves 21 in the stud portion thereof into which grooves project screws 22 locked in place by nuts 23 in order to hold the pinions 20 in position. Each pinion 20 has a

square front portion 24 to receive a suitable end wrench which may be inserted through openings 25 in drum heads 26.

The stud pinion gears 20 mesh with large gears 30 formed on externally threaded sleeves 31. Externally threaded sleeves 31 fit in internally threaded hub portions 32 of the drum heads 26. The gear portions 30 are held close to the holders 18 by means of guiding members 33 which are secured to the holders 18 by means of bolts 34.

10 Projecting inwardly from each head 26 is a plate 35 having a slot 36 in which fits a pin 37 attached to and projecting inwardly from the drum 11. When the wrench is inserted in one of the holes 25 and the stud gear 20 is rotated, the gear 30 is revolved and one direction of rotation forces the corresponding head 26 outwardly. However, owing to the pin 37 and slot 36, the head in question must slightly revolve during its outward movement. The pitch of the slot 36 is 15 such as to force the drum heads 26 outwardly in a spiral direction which has the same pitch as the abrasive paper or other abrasive sheet material 40 on the drum 11.

20 The present invention includes simplified and highly effective clamps for clamping the abrasive paper 40 to the drum heads 26. Referring now to Figures 1, 2, and 3, the clamps which are designated as a whole by the numeral 41 are preferably three in number for each drum head 26, that is to say there are six clamps in all. Each of these clamps 41 may be just like every other one and any clamp will go on either end of the drum. Each clamp 41 comprises a 120° arcuate end portion 42 fitting over the ends of annular flanges 43 of the drum heads 26 together with an outside inwardly extending lip 44 also extending 25 120° around the circle and an inside inwardly extending lip 45 likewise extending 120° around the circle. I provide two bolts 46 for each clamp 30 41 extending through the lip 45 and abutting the flange 43. I may provide more bolts 46, if desired, but two thereof are found to be adequate.

35 Considering now the mounting of paper or cloth upon the drum 11, I cut the sheet material into the parallelogram shape shown in Figure 4. I prefer to use abrasive paper. I then wind the paper on the drum 11, as shown in Figure 3, and place the three clamps 41 in position and tighten the bolts 46. If the paper is wrinkled in any place, one of the clamps may be loosened and the paper smoothed out and then such clamp retightened. In placing the paper on the drum 11, I bring the edges together to form as narrow an opening or seam 50 as possible. I do not overlap 40 50 55

the paper unless there is a groove in the drum 11 provided for that purpose. With the present improved clamps and drum in a leather surfacing machine of the type illustrated herein and to be described and when surfacing certain leather materials, I may use a cylindrical drum 11 without any groove, but for other conditions of operation I prefer to use a groove and overlap the paper, as disclosed in copending application of Seymour 10 J. Hallsted, Serial No. 21,733.

I now place the wrench in one of the openings 25 and turn the pinion stud 20. In order not to cause the paper to wrinkle I tighten first one and then the other of the pinion studs 20 and experience will soon show an operator how to tighten the paper without producing wrinkles as sometimes one and sometimes the other of the pinion studs should be turned the most to tighten the paper without producing any wrinkles therein. 20 When the last pinion stud 24 to be tightened has been turned about as tight as it can be with the strength of an ordinary man, the paper is properly applied and friction holds the paper taut and prevents slippage.

25 Referring now to Figure 5, I shall briefly describe the machine in which the abrasive drum is preferably used and in connection with which it presents the features and advantages hereinbefore indicated. This machine is more fully described in the aforesaid copending application of Seymour J. Hallsted and also in my own copending application Serial No. 20,963. Such a machine includes a pair of side frames 51 only one of which is shown in Figure 5. These side frames may be of inverted U-shape, thus collectively constituting the four legs of the machine. There is further provided for each side frame member a fore and aft connecting frame member 52 which may be U-shaped in cross-section. 40 There is provided at the front and back of the machine frame members 54 and 55 respectively, connecting the legs of the U-shaped side frames and which frame members 54 and 55 are X-shaped when viewed in front elevation.

45 The front part of the top of each side frame 51 is milled or otherwise suitably surfaced to provide a smooth slideway and upon these surfaces are mounted a pair of similar slides 56 having depending aprons 57, one on each side of each slide 56 in order to guide the slides for rectilinear motion. Extending from the inside of the horizontal portion of the frame members 51 are studs 60 upon which are mounted bell crank levers 61 having arms extending vertically and horizontally. In the vertical arm of each bell crank lever 61 is a slot 62 and in these slots are studs 63 fastened to the aprons 57. The horizontal arms of the bell crank levers 61 are connected by means of pins 64 to links 65 extending downwardly to levers 66, the links 65 being connected to the levers by means of pins 67. The levers 66 are freely movable upon a shaft 69 which extends between brackets 70 bolted to the under side of the frame members 52. Projecting laterally from the rear ends of the levers 66 are square pins 71 each adapted to receive one or a plurality of detachable weights 72. Connecting the front portions of the levers 66 is a wooden plank treadle 70 member 73. Thus in a manner more fully described in the aforesaid application of Hallsted, the slide 56 may be moved to the front of the machine, that is toward the operator whenever he steps upon the plank 73, and the operator may 75 move one side of the slide 56 more than the

other by stepping upon one side or the other of the plank 73.

Still referring to Figure 5, uprising from the slides 56 are journal members 80 mounting a shaft 81. Secured to the shaft 81 and between the journals 80 is a rubber covered roller 82. In order that there shall be no binding of the shaft 81 in the journals 80, these journals are swiveled on the slides 56 by means of vertical trunnions 83 for the journal member 80 which rest in vertical bores of annular supporting members 84 for the journals 80.

10 There is provided a drive for the rubber feed roller 82, not illustrated herein but which may be as shown in my aforesaid copending application or may be of the type shown in my U. S. Patent No. 1,975,349. The rubber covered roller 82 is driven in a clockwise direction and at a very much lesser angular velocity than the abrasive drum 11. The abrasive drum 11 is preferably 15 driven by direct drive connection to a motor, not shown, the shaft 10 being mounted in suitable journal blocks 85.

20 There is provided a pinch roller 90 preferably of steel which cooperates with the rubber roller 82 to feed the leather goods or other material. The pinch roller 90 is mounted upon a shaft 91 which in turn is mounted in journal portions in the front of long arms 92 that are articulated on pins 93 to the upper forked ends 94 of standards 95 adjustably secured to the side frame members 51. The standards 95 are securely but adjustably secured to the side frames 10 and are U-shaped; they have front upright portions 96 with horizontal inwardly extending portions 97 receiving bolts 98 that extend through the arms 92 and also providing a surface to receive the ends of bolts 99. The bolts 99 are threaded into the arms 92 but the bolts 98 are received loosely in holes in the arms 92. Consequently the arms 92 may be raised and lowered by turning the bolts 99, and when the desired position of adjustment is reached the parts can be securely locked by tightening the bolts 98.

25 The leather to be treated is placed by the operator upon a table 100 extending between supports 101 bolted to the slides 56, and the operator first steps upon the treadle platform 73 to withdraw the rubber roller 82 from the drum 11 whereupon he places the leather under the pinch roller 90 and allows the rubber roller 82 to move toward the drum 11. The machine then feeds the leather toward the abrasive drum 11, the front side of which is moving downwardly. The clamping and tightening means for the abrasive paper cooperates with the features of the machine described and particularly the adjustment features to permit a very fine finish within very close tolerances to be achieved. The clamp of the invention holds the abrasive paper with adequate tightness to withstand the very heavy friction involved in finishing glove leather and the like. In the preferred embodiment of the invention the abrasive paper is wound once and a half times around the drum 11. The abrasive paper can be cut to the parallelogram shape shown in Figure 4 because, in accordance with this invention, there is no obstruction on the ends of the drum interfering with the paper. In other words the drum is a plain cylindrical drum and the heads are extensions thereof. The clamps are U-shaped in cross section which permits them to be fitted over the flanges 43 and at the same time they are virtually 120 degree segments of a circle. The bolts 46 constitute positive means 30 35 40 45 50 55 60 65 70 75 80 85 90 95 100 105 110 115 120 125 130 135 140 145 150 155 160 165 170 175 180 185 190 195 200 205 210 215 220 225 230 235 240 245 for holding the clamps 42 firmly against the external periphery of the flanges 43 of the heads 26.

The abrasive material preferably comprises aluminum oxide abrasive grain, such as is produced in the electric furnace, fixed upon a sheet of suitable paper with a glue binder. However, other abrasive materials, such as silicon carbide, garnet and the like, may be used and other binders, for example suitable phenolic resin binders, if desired, the abrasive grains may be oriented, as by the electrostatic method of deposition which is now understood in this art.

It will thus be seen that there has been provided by this invention an apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:—

1. An abrasive drum comprising a metal cyl-

inder, a pair of heads for said abrasive drum, means to move the heads outwardly in a spiral course, and a plurality of clamps to hold sheet abrasive material to the heads and thereby to hold it on the drum, each clamp being in the form of a segment of a circle and U-shaped in cross-section and having a plurality of bolts, and flanges on the heads to receive the clamps.

2. An abrasive drum comprising a metal cylinder, a pair of heads for said abrasive drum, means to move said heads outwardly, and a plurality of clamps to hold sheet abrasive material to the heads, each clamp being in the form of a segment of a circle, and means to hold the clamps against the peripheries of the heads.

3. In apparatus of the class described a shaft, a drum on said shaft, a pair of heads to said drum, means to move said heads away from each other, a flange on each head, and a clamp fitting over the end of each flange, and means to draw each clamp toward said shaft.

4. In apparatus of the class described, a segmental clamp U-shaped in cross section and bolts on the inside of the clamp.

GEORGE MONROE CURTIN. 25
